T. LIPTÁK

STOVE LID LIFTER

Filed Aug. 14, 1923

FIG. 1.

FIG. 2.

Inventor

T. Lipták

By

J. K. Bryant
Attorney.

UNITED STATES PATENT OFFICE.

TEREZ LIPTÁK, OF PUNXSUTAWNEY, PENNSYLVANIA.

STOVE-LID LIFTER.

Application filed August 14, 1923. Serial No. 657,346.

To all whom it may concern:

Be it known that I, TEREZ LIPTÁK, a citizen of Hungary, residing at Punxsutawney, in the county of Jefferson and State of Pennsylvania, have invented certain new and useful Improvements in Stove-Lid Lifters, of which the following is a specification.

This invention relates to new and useful improvements in stove lid lifters.

An important object of the invention is to provide a lid lifter of a construction that will insure obtaining a rigid grip upon a stove lid for preventing relative movement therebetween after the lid has been removed from the stove.

A further object of the invention is to provide a device of the above mentioned type which is of simple construction, strong, durable, and one that may be manufactured at a very nominal cost.

Other objects and advantages of the invention will be apparent during the course of the following description.

In the accompanying drawing forming a part of this specification and in which like numerals are employed to designate like parts throughout the same,

Figure 1 is a side elevational view of the stove lid lifter embodying this invention and shown in position for lifting the stove lid illustrated in section, and

Figure 2 is a top plan view of Fig. 1.

In the drawing, wherein for the purpose of illustration is shown a preferred embodiment of this invention, the numeral 5 designates a fragmentary portion of a stove top which is provided with an opening 6 adapted to be closed by the lid 7 having a depression formed therein that consists of the arcuate bottom wall 8 and having a transversely extending pin 9.

The lifter consists of the crossed members A and B which are provided with handle portions 10 and 11 respectively. The member A is provided with a downwardly curved forward end 12 having a bifurcated arcuately-shaped clamping jaw which consists of the spaced parallel side arms 13 and 14. These arms 13 and 14 are provided with integrally formed upstanding lugs 15 which are spaced inwardly from the extreme ends of the said arms. The member B is provided with a reversely curved portion 16 which is positioned between the inner ends of the spaced parallel side arms 13 and

14 and is pivotally connected thereto by the pin or rivet 17. The straight clamping jaw 18 is formed integrally with this reversely curved portion 16 and is provided at its outer end with an integrally formed depending lug 19 that is spaced outwardly of the lugs 15 carried by the side arms 13 and 14. The handle portions 10 and 11 are provided with a coil spring 20 which is seated at its opposite ends in recesses 22 formed in the inner faces of the same and is adapted for normally retaining the clamping jaws in the positions shown in Figs. 1 and 2.

By inspecting Fig. 1, it will be seen that when the handle portions 10 and 11 are forced together against the tension of the spring 20, the clamping jaws will be separated for allowing the spaced parallel side arms of the arcuately-shaped lower jaw to be positioned within the depression formed in the stove lid 6 with the said arcuate jaw engaging the curved surface 8. The transversely extending pin 9 will engage the upstanding spaced lugs 15 and will be held thereagainst when the handle portions 10 and 11 are released for allowing the spring 20 to move the upper jaw 18 toward the lower arcuate bifurcated jaw and for positioning the depending lug 19 on the opposite side of the pin 18 to the upstanding lugs 15. It will be seen that this construction will prevent tilting of the lid 7 in any direction in respect to the said lifter.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a lifter, a pair of crossed members pivotally connected, a handle portion formed on each member, a bifurcated clamping jaw carried by one member, a clamping jaw carried by the second member extending through said bifurcated jaw, spaced lugs carried by said bifurcated jaw, a single lug carried by the second clamping jaw, and means carried by said handle portions for causing said clamping jaws to move toward each other.
2. In a lifter, a pair of crossed members pivotally connected, a handle portion

formed on each member, a clamping jaw consisting of spaced parallel side arms having lugs spaced inwardly from their outer ends carried by one member, a straight jaw having a depending lug positioned outwardly from the first mentioned lugs carried by the second member, and means associated with said handle portions for moving said clamping jaws toward each other.

3. In a lifter, a pair of crossed members pivotally connected, a handle portion formed on each member, an arcuate bifurcated clamping jaw carried by one member, a straight clamping jaw extending outwardly of the bifurcated jaw carried by the second member, and a coil spring positioned between said handle portions for normally retaining said clamping jaws in operative relation in respect to each other.

4. The combination with a stove lid having a recess provided with a curved bottom wall and a transversely extending pin positioned within said recess, of a lifter consisting of a pair of crossed members pivotally connected, a handle portion formed on each member, an arcuate bifurcated jaw having upstanding lugs carried by one member adapted for engaging the curved bottom wall of the recess with the lugs engaging one side of the transversely extending pin, and a straight jaw having a depending lug positioned outwardly of said first mentioned lugs carried by the second member adapted for engaging the opposite side of said transversely extending pin.

In testimony whereof I affix my signature.

TEREZ LIPTÁK.
